UNITED STATES PATENT OFFICE

RUDOLF SCHENK, OF VIENNA, AUSTRIA, ASSIGNOR TO WESTERN ELECTRIC COMPANY,
INCORPORATED, OF NEW YORK, N. Y., A CORPORATION OF NEW YORK

TELEPHONE SYSTEM

Application filed October 20, 1928, Serial No. 313,685, and in Austria May 14, 1926.

This invention relates to telephone systems and particularly to busy signaling arrangements for manual common battery systems.

5 In accordance with common practice a manual operator tests for the idle or busy condition of a called line by touching the tip of the calling plug to the sleeve of the multiple jack of the called line. If such called line is busy the result of this test is a click produced in the operator's receiver. The operator may then report the busy condition found to the calling subscriber either orally or by plugging into a "busy back" jack. 10

15 Either of these operations consumes time and ultimately results in the employment of a large operating force.

According to the present invention the busy signaling arrangement for notifying 20 the calling subscriber that the called line is busy is associated with the cord circuit and is started into operation upon the usual busy test being made. Thus when the tip of the calling plug is touched to the sleeve of a 25 busy line jack, the busy back arrangement is immediately brought into action and signals both the calling subscriber and the operator that the called line is busy and maintains this signal until the connection to the calling 30 subscriber is taken down.

The drawing is a diagrammatic illustration of the present invention.

Connection is established to the calling subscriber by inserting the plug A. S. of an 35 idle connecting cord into the jack K. *a*. Thereby the following circuit is closed: earth over winding of relay T. R., jack sleeve and *c* contact of the plug, winding of relay A. R. over contact 3 of relay S. R. to battery. 40 Relay T. R. and relay A. R. are caused to operate. The operator's telephone is connected to the calling subscriber at the contacts 1 and 3 of the relay A. R. When the operator has learned the wanted number she puts 45 the tip S. of the connecting plug V. S. to the sleeve H of the jack of the called line. If the called line is busy i. e. if the plug of another connecting cord KO II has been inserted in another multiple jack K_b₁, then the 50 plug tip S will connect battery over the

C-wire and winding of relay S. R. of the connecting cord KO II to the winding of relay B. R. over contact 1 of S. R. While the connection between plug tip S. and jack sleeve H is maintained relay B. R. is energized and 55 its contact 1 is closed, whereby battery is connected to the winding W I of relay SU. R. Relay SU. R. becomes energized and locks in a circuit from ground, winding W II of relay SU. R. and its contact 4, contact 2 of 60 relay A. R. to battery. Consequently when the plug tip S. is removed from connection with the jack sleeve H and relay B. R. returns to normal, relay SU. R. will remain 65 energized.

At contact 1 of SU. R. a circuit is closed for busy lamp BL so that the operator has a visual indication that the called line is busy.

Contact 2 of relay SU. R. connects a source of tone SU. to the connecting point S₁, from 70 which tone current flows over contact 3 of relay A. R., ring contact R of plug A. S., the *a* wire of the calling telephone line, the receiver at substation SP., the *b* wire, tip contact S of plug A. S. and winding of retardation coil D. S. to battery. The subscriber at substation SP. hears this tone and 75 is thereby signalled that the called line is busy.

Tone current applied to the connecting 80 point S₁ also flows over the operator's telephone T., condenser K, secondary winding of induction coil I. S., high resistance W_i, contact 1 of relay A. R. and winding of retardation coil D. S. to battery. The operator receives this tone signal weakened by 85 the high resistance W_i.

The operator now removes the answering 90 plug A. S. from the jack. Thereby relay A. R. is deenergized and returns to normal. Contact 2 of relay A. R. disconnects battery from the holding winding W II of relay SU. R. which thereupon returns to normal. Contacts 1 and 2 of relay A. R. open and the 95 visual and audible busy signals are cut off. Contact 3 of relay A. R. closes and short circuits the high resistance W_i in series with the operator's telephone set.

What is claimed is:

1. In a telephone system, a calling line, a 100

circuit terminating at one end in a connection to said calling line and at another end in a cord and plug, a source of tone current, a busy lamp and an operator's set associated with said circuit, a called line terminating in a jack, and means responsive to a transient connection between the tip of said plug and the sleeve of said called line jack for connecting said source of tone current to said calling line and said operator's set and for lighting said busy lamp.

2. In a telephone system, a calling line, a circuit terminating at one end in a connection to said calling line and at another end in a cord and plug, a source of tone current and an operator's set associated with said circuit, a called line terminating in a jack, means responsive to a transient connection between the tip of said plug and the sleeve of said called line jack for connecting said source of tone current to said calling line and said operator's set and means for attenuating the tone current in said operator's set.
